UNITED STATES PATENT OFFICE.

JOSEPH FORMAN, OF BALTIMORE, MARYLAND.

GARMENT-FASTENER.

No. 888,987.

Specification of Letters Patent. Patented May 26, 1908.

Application filed April 20, 1907. Serial No. 369,195.

To all whom it may concern:

Be it known that I, JOSEPH FORMAN, a citizen of the United States, residing at Baltimore, in the State of Maryland, have invented certain new and useful Improvements in Garment-Fasteners, of which the following is a specification.

This invention relates to garment fasteners and is designed to be attached to the 10 overlapping separable portions of garments to hold said portions together.

One object of the invention is to provide a fastener which may be attached to the garment in such a manner as to cause the strain 15 to be applied directly to the garment material and not depend upon stitching.

Another object of the invention is to provide a simple and inexpensive fastener that may be formed by dies from sheet metal and 20 which will present a neat appearance when applied to the garment.

With these and other objects in view the accompanying drawing illustrates the invention in which,—

25 Figure 1 illustrates a portion of a garment the overlapping edges of which are provided with the improved fastening. Fig. 2 illustrates perspective views of the two fastener parts in their proper relative positions with 30 respect to each other. Figs. 3 and 4 illustrate views of the flat blanks from which the two fastener parts are formed. Fig. 5 shows an enlarged cross-sectional view of the overlapped edges of the garment and fastener parts in the interlocked position. Fig. 6 35 shows a cross-sectional view through the interlocked fastener,—the section being taken in the line 6—6 of Fig. 5. Fig. 7 illustrates a similar view,—the section however being 40 taken on the line 7—7 of Fig. 5, and Fig. 8 shows a horizontal section through one flap of the garment with the head part engaged therewith.

Referring to the drawing by numerals, 1, 45 designates the head portion of the two part fastener and, 2, the hook portion thereof. The head part of the fastener comprises the flat disk or plate, 3, and the arms, 4, and, 5, formed integrally therewith. The metal 50 from which this head part is formed is folded or bent at, 6, adjacent to the edge of the disk, or plate, 3, while a similar bend or fold, 7, connects the arms, 4, and 5. The crotch, 8, thus formed by the fold, 6, performs an important function in the operation of the fastener as will presently be described.

The arm, 5, it will be noted is longer than the arm, 4, and said longer arm is provided at its end with a perforation, 9.

The flap portion, 10, of the garment is provided with a short vertical slit, 11, and the arms, 4, and 5 of the head fastener are passed through this slit,—the perforated end of the arm, 5, first being passed through by moving it in a horizontal direction away from the 60 vertical edge, 12, of the flap, 10, and the arm, 4, then being passed through the slit by moving the fastener in a horizontal direction back toward said vertical edge, 12. When this head portion of the fastener is in its proper 70 position with respect to the vertical slit, 11, in the garment flap, the vertical edge, 13, of the slit will have position in the crotch, 8, between the head, 3, and arm, 4, and it will be seen that any direct horizontal pull on the 75 head in the direction of the vertical edge, 12, of the flap will only tend to wedge the edge, 13, in said crotch and the head part cannot be pulled out of the slit by being drawn in such a direction. Stitches, 14, are preferably taken 80 through the perforation, 9, and the material of the garment adjacent thereto and these stitches serve to keep the end of the arm, 5, close against the inner side of the garment flap. By this manner of attaching the head 85 portion of the fastener to the garment flap the retention of the head in place does not depend upon the stitches, 14, but more on the edge, 13, of the slit, 11.

The hook portion of the fastener may vary 90 in its construction and manner of attachment but in the present instance this hook portion comprises a flat base plate, 15, having perforations 16, for securing it by stitches to the flap, 17, of the garment; a hook plate, 95 18, and a curved arm, 19, connecting the hook plate and the base plate.

The hook plate has a central notched or cut away portion, 20, and a finger or leg, 21, at each side thereof. The width of this 100 notch, 20, between the two fingers or legs is such as to enable it to straddle the fold or bend, 6, at the end of the arm, 4, so that when the two fastener parts are engaged the fingers or legs, 21, will project behind the 105 disk or plate, 3, and straddle the arm, 4.

Having thus described my invention, what I claim as new and desire to secure by Letters Patent is,—

1. A garment fastener comprising a hook 110 member for attachment to one flap of the garment and a head member for attachment

to the other flap of said garment,—said head member having an outer plate, an arm formed integrally with said head and extending laterally from one edge thereof and forming a crotch adjacent to said edge, said arm being narrower than said head and a second arm having one end connected to the front arm and extending in a direction back toward said crotch and having a perforation in its free end.

2. A garment fastener comprising a head member having an outer plate and reversely

projecting arms carried by said plate from one edge thereof and a hook member having spaced apart legs which straddle one of the 15 arms of the head member and project behind the plate of said head member.

In testimony whereof I affix my signature in presence of two witnesses.

JOSEPH FORMAN
